SULKY FOR A FOLDABLE GOLF CART

Robert W. Stuart, 955 Caniff Road,
Columbus, Ohio 43221

Filed Dec. 19, 1966, Ser. No. 5,105

Term of patent 7 years

(Cl. D14—3)

FIG. 1.

FIG. 2.

FIG. 3.

FIG. 4.

FIG. 5.

FIG. 6.

FIG. 7.

FIG. 1 is a side elevational view of a sulky for a foldable golf cart in folded condition;

FIG. 2 is a similar view thereof in partially open condition;

FIG. 3 is a similar view thereof in open condition;

FIG. 4 is a top plan view thereof;

FIG. 5 is a rear elevational view thereof;

FIG. 6 is a front elevational view thereof;

FIG. 7 is a side elevational view.

The broken line showing of the drive unit in FIG. 7 is for illustrative purposes only.

I claim:

The ornamental design for a sulky for a foldable golf cart, as shown and described.
